COMBINED TABLE AND CABINET

Richard James Dunlap, Colorado Springs, Colo.

Application September 21, 1951, Serial No. 16,702

Term of patent 14 years

(Cl. D33—14)

To all whom it may concern:

Be it known that I, Richard James Dunlap, a citizen of the United States, residing in Colorado Springs, El Paso County, State of Colorado, have invented a new, original, and ornamental Design for a Combined Table and Cabinet, of which the following is a specification, reference being had to the accompanying drawing, forming a part hereof.

Fig. 1 is a front perspective view of a combined table and cabinet, showing my new design;

Fig. 2 is a similar view but with the cabinet shown open;

Fig. 3 is an end elevational view of the combined table and cabinet, shown in Fig. 1; and

Fig. 4 is a rear elevational view of the same.

I claim:

The ornamental design for a combined table and cabinet, as shown.

RICHARD JAMES DUNLAP.
